UNITED STATES PATENT OFFICE.

HARRY M. ROBERTSON, OF CLEVELAND, OHIO, ASSIGNOR TO AMERICAN DRESSLER TUNNEL KILNS, INC., OF NEW YORK, N. Y., A CORPORATION OF NEW YORK.

COMBINATION OPEN AND MUFFLE KILN AND METHOD OF OPERATING THE SAME.

Application filed December 11, 1920. Serial No. 429,867.

To all whom it may concern:

Be it known that I, HARRY M. ROBERTSON, a citizen of the United States, and resident of Cleveland, in the county of Cuyahoga and State of Ohio, have invented certain new and useful Improvements in Combination Open and Muffle Kilns and Methods of Operating the Same, of which the following is a specification.

10 The general object of my present invention is to provide a novel and effective continuous tunnel kiln especially adapted for use in burning and flashing or salt glazing brick, drain tile and analogous ceramic ware.

More specifically the object of my invention is a kiln having novel and effective provisions for obtaining the desired temperature graduations along the length of the kiln chamber and the maintenance of the proper flashing, glazing or other special atmosphere required in a high temperature zone of the kiln intermediate the heating up and cooling zones or ends of the kiln.

25 In carrying out my invention I supply heat to said intermediate kiln zone by passing burning gases and hot products of combustion through the goods receiving space in this portion of the kiln chamber, and heat the heating up zone portion of the kiln by means of muffles or combustion chambers through which flow burning gases or hot products of combustion. I am thus enabled to maintain an atmosphere in the goods receiving zone of this portion of the kiln which is independent of the character of the gases passing through the muffles or combustion chambers. Advantageously and preferably the combustion chambers or muffles are of 30 the well known hollow wall type employed in the ordinary Dressler tunnel kilns.

The various features of novelty which characterize my invention are pointed out with particularity in the claims annexed to and forming a part of this specification. For a better understanding of the invention, however, of the advantages possessed by it, and specific advantages attained with it, reference should be had to the accompanying drawings and descriptive matter in which I have illustrated and described preferred forms of apparatus.

Of the drawings:

Fig. 1 is a somewhat diagrammatic plan view partly in section;

Fig. 2 is a partial section elevation taken on the broken line 2—2 of Fig. 1;

Figs. 3, 4 and 5 are transverse sections taken respectively on lines 3—3, 4—4, and 5—5 of Fig. 1;

Fig. 6 is a partial section taken on the line 6—6 of Fig. 4; and

Fig. 7 is a view taken similarly to Fig. 1 illustrating a modified construction.

The kiln A shown in Figs. 1—6 of the drawings is formed with masonry walls including an arched roof as is usual in tunnel kilns, and comprises a preheating zone A', a cooling zone A³ and an intermediate high temperature zone A². The goods treated in the kiln are moved slowly through the latter on cars B running on track rails B', the cars entering the kiln at the preheating end of the latter and leaving the kiln at the cooling end.

To heat the kiln I employ furnaces C, of which 12 are shown, arranged six at each side of the kiln in a series running the length of the furnace zone A² of the kiln. Advantageously, as shown, each of the furnaces C is of the so-called furnace gas producer type, and comprises a chamber having refractory walls into which solid fuel, as coal or coke, is passed as required through a hole C' normally closed by a door C¹⁰. At its inner side each furnace chamber is open to the kiln chamber at C². At the bottom of each furnace chamber is provided a grate D, which, as shown, is of a known type made of cast iron with trunnion supports D' and D², journaled in bearings provided in the metallic grate support D³. The grate D which is hollow normally occupies the position shown in full lines in Figs. 4 and 6 but may be swung into the position shown in dotted lines in Fig. 6, to dump the furnace contents into the ash pit C⁴ provided beneath each furnace chamber. The outer trunnion D' of each grate D is hollow and open at its outer end. In operation, atmospheric air is drawn into each hollow grate through its trunnion D' by the kiln draft supplemented by the injector action of a steam nozzle E discharging axially into the hollow trunnion D' and receiving steam from a supply piping D⁵. Each grate D is formed with an air and steam outlet D⁶ at its upper side and is provided with a hood D⁷ preventing fuel and ashes from passing into the hollow

grate through its outlet D³. C⁶ represents an opening in the outer wall of each furnace chamber at and above the grate level through which the fire may be inspected and ashes may be removed. As shown each opening C⁶ is normally closed by a door or cover gate C⁶.

Interposed between the goods receiving space in the furnace zone section of the kiln 10 and the furnace outlets C² at each side of the kiln is a corresponding baffle wall F which extends nearly, but not quite to the roof of the kiln chamber, and advantageously has its outer side inclined as shown in 15 Fig. 4 to deflect the burning gases entering the kiln chamber through the furnace outlets C² to the top of the kiln chamber. Ordinarily and preferably, ports F' are formed in the upper portion of each wall 20 F. Advantageously for structural reasons and to restrict the flow of burning gases longitudinally of the kiln in the furnace zone portion of the latter, transverse walls G are provided as shown at intervals across 25 the space between the outer side of each baffle wall F and the adjacent kiln wall. As shown the walls G are arranged one between each adjacent pair of furnaces C and extend to the roof of the kiln chamber 30 proper.

Located in the base of each wall F is a conduit H running longitudinally of the kiln through the furnace zone A². Lateral passages H' open into each conduit H at intervals along its length from the goods receiving space of the kiln. The passages H' open to the kiln chamber proper adjacent the level of the goods supporting platforms of the cars B, and preferably so as to register with the transverse channels B² which are formed in the car bodies and are open at their upper edges.

Products of combustion passing from the kiln chamber proper through the passages H' into the conduits H issue from the latter into muffles or conduits J which extend longitudinally of the kiln chamber through the preheating zone A' thereof, and communicate at the end of the kiln through ports K' and a tunnel K² with a suitable draft creating device shown as the stack K. The walls of the conduits J are preferably formed as shown of hollow tile sections, the passages J' in which form channels for the circulation of the kiln atmosphere as indicated by the arrows in Fig. 5. The conduits H are thus of the same construction and perform the same kiln heating and temperature equalizing functions as the so-called combustion chambers commonly employed in the continuous tunnel kilns of the well known Dressler type. To regulate the kiln draft the conduits H may each be provided with a damper H². Advantageously the conduits 50 or muffles J extend only something like

halfway from the benches A⁶ on which they rest to the top of the kiln chamber. To restrict undesirable longitudinal flow of the kiln atmosphere from the furnace zone A² of the kiln chamber into the preheating zone 70 A', I provide baffles I which project outwardly from the combustion chambers and depend from the roof of the kiln chamber into proximity with the space traversed by the goods mounted on the goods carrying 75 cars B.

The cooling zone A³ of the kiln is formed with double side and roof walls so that in effect it comprises two tunnels, one within the other. Atmospheric air is allowed to 80 pass into the chambers L between the double side walls of the cooling zone through ports L' formed in the outer wall. These ports may be throttled more or less by dampers or brick forming throttling devices L². Passages L³ are formed in the inner side walls of the cooling zone through which air may pass into the kiln chamber from the chamber L. The passages L³ may be wholly 85 or partially closed by bricks L⁴ which can be adjusted through the ports L'. The ports L' and L³ are advantageously distributed along the length of the cooling zone. The chambers L communicate at their upper 90 edges with the chamber M between the double roof walls of the cooling zone portion A³ of the kiln. The chamber M is connected adjacent the junction of the zones A² and A³ to vertical conduits O one at each side 95 of the kiln. These open at their lower ends into a tunnel O' leading to a suitable draft device shown as a stack KA.

Ordinarily and preferably air pipes N are provided for cooling the track rails B' and the metallic under portions of the goods carrying cars B. As shown these pipes may receive atmospheric air under pressure from a fan N⁴, through the supply connection N' or may receive air at atmospheric pressure through the pipes N² and N³. As shown in 100 Fig. 1 provisions are made for using the heated air issuing from the pipes N in whole or in part as the secondary air of combustion for the furnace C. The air thus used passes from the tunnels or conduits K¹⁰ or K¹¹ to which the pipes N discharge, into piping P provided with a branch connection P² to each furnace chamber. These branch connections are each controlled by individual valves P³ and as shown, each enters the corresponding 105 furnace chamber through the wall portion between the openings C' and C⁶. The conduits K¹⁰ and K¹¹ are also connected to the stacks K and KA, respectively, and each includes a cut off or throttling damper K¹² by which it may be wholly or partially disconnected from the corresponding stack. Valves P' are provided in the piping P adjacent its connection to the tunnels K¹⁰ and K¹¹. Valves N³ are provided for connect- 110 115 120 125 130

ing the pipes N' either directly to the atmosphere through the branch pipes N^2 or through the fan N^4 according to the mode of operation desired.

Assuming first that the valves N^8 in the pipe N^2 are closed, while the valves N^3 connecting the fan N^4 to the pipes N' are open and that the valves I' are open and dampers K^{12} are wholly or partially closed, the operation of the apparatus shown in Figs. 1-6 is as follows:

Primary air passes into the bottom of each furnace chamber C through the corresponding hollow grate D under the draft due to the stack K which may be supplemented by the injector action of the steam jets discharged by the nozzles E . The combustible gas generated by the passage of the steam and air into the fuel bed in each furnace C unites in combustion as it rises from the fuel bed with the secondary air supplied through the pipes P^2 . The burning and burnt gases pass from each combustion chamber through the corresponding outlet C^2 into the kiln chamber proper and are diverted toward the top of the kiln chamber by the adjacent baffle wall F . The bulk of the burnt and burning gases passes into the goods receiving portion of the kiln chamber over the tops of the walls F but a portion of these gases passes through the ports F' . From the upper portion of the kiln chamber the gases pass downward along and through the spaces between the goods on the cars B to the platforms of the latter, and into the channels B^2 in the car platforms and thence passes into the conduits H through the passages H' . From the conduits H the gases pass into the muffles or combustion chambers J and finally pass from the latter into the stack K .

In normal operation the major portion of the available heat in the burning gases passing into the kiln chamber from the furnace chambers C is retained by the gases when they enter the combustion chamber or muffles J , and is transmitted to the goods in the heating up zone of the kiln. The temperature of the heating up zone rises gradually from the end of the kiln to the high temperature zone A^2 , and the transfer of heat from the muffles or combustion chambers J to the goods in the heating up zone is mainly effected by convection currents of the kiln atmosphere as in the ordinary Dressler kiln, these convection currents passing through and being directed by the open ended channels J' in the walls of the muffles. The flow of the convection currents is indicated in a general way by the arrows in Fig. 5. The downward flow of the kiln atmosphere through the goods receiving space of the kiln, which is characteristic of the operation of an ordinary Dressler kiln, has a highly desirable and well recognized tendency to

equalize the temperatures at all points in any transverse vertical plane through the kiln chamber. Exactly the same downflow of the kiln atmosphere and resultant heat equalizing effect is obtained in the high temperature open fire portion of my improved kiln with the special arrangement of furnace chambers C , baffle walls F and outlet connections H' shown. The withdrawal of the burning gases from the kiln chamber through the outlet passages H' from the high temperature zone A^2 tends to cause air leaking into the kiln at its entrance end or into the cooling zone of the kiln to flow from the end portions of the kiln into the zone A^2 , and prevents any appreciable flow of the gases from the zone A^2 of the kiln into the other kiln zones. This is especially important in the case of the heating up zone A^1 , wherein it is, in general, desirable to maintain a highly oxidizing atmosphere, while in the zone A^2 , the atmosphere should in general, be either neutral or reducing in order to secure a flashing or salt glazing effect. Whether the atmosphere in the zone A^2 is reducing, neutral or oxidizing, depends on the relative amounts of secondary air supplied to the pipes P^2 , and is controlled by the valves P^3 , which are opened to make the atmosphere oxidizing and throttled to make it reducing. When salt glazing is desired the salt is vaporized in the furnace chambers C into which it may be fed in any suitable manner as, for instance, by mixing it with the coal thrown from time to time, on the tops of the fuel beds in the furnace chambers. The special producer furnace construction employed is not of itself novel with me except in the special relation in which I employ it, but on the contrary is of a type which has been found highly desirable because of the efficiency of the combustion obtainable and the relatively small labor cost of operation.

While I consider it generally desirable to increase the efficiency of the apparatus by using as the secondary air, preheated air, withdrawn from the truck cooling pipes N as shown or from other cooling apparatus of the kiln, the latter will operate satisfactorily with unheated secondary air drawn into the furnace chamber tunnel from the atmosphere by the kiln draft suction. When it is desired to operate the apparatus shown in Figs. 1 to 6 in this manner, the valves N^8 are manipulated to connect the pipes N' to the atmosphere through the pipes N^2 , and the valves I' are closed. Secondary air may then be admitted to the furnace chambers C through the openings C^8 , by opening the doors or cover plate C^6 , or by opening dampers normally closing openings C^7 in said cover plates.

The special cooling zone section described possesses obvious advantages of simplicity

and ruggedness in construction, and forms an effective means for cooling the ware down to the proper temperature for removal from the kiln. The amount of air permitted to 5 pass into the kiln chamber proper from the ports L^3 depends, in general, upon the character of goods being handled. With finer and more delicate ware little or no air should pass into the kiln chamber through the ports 10 L^3 , while with coarser, stronger ware considerable quantities of air may advantageously be introduced.

By properly adjusting the dampers K^{13} controlling the suction effects of the two 15 stacks K and KA or other draft producing devices, the kiln may be operated without any appreciable longitudinal flow of the kiln atmosphere from one of the zones A^2 and A^3 into the other, even though the ports 20 L^3 are wide open the full length of the cooling zone A^3 . It will be understood, of course, that the hot air withdrawn from the hollow walls of the cooling zone section of 25 the kiln or from the truck cooling pipes N can be advantageously used in driers or for analogous purposes in many cases.

The modified form of apparatus shown in Fig. 7 differs from that shown in Figs. 1 to 6, primarily in that the conduits H are 30 connected directly to a stack KB , and the combustion chambers JA in the preheating zone of the kiln are heated by combustion occurring in those chambers of fuel gas and air for its combustion which may be supplied to the chambers in any suitable or 35 usual manner. As shown fuel gas is supplied to the chambers JA through conduits Q from producers Q' but no provision for supplying air to the chambers JA is illustrated and none need be described as this air and indeed the fuel gas may be supplied in 40 any of the known ways such as are commonly employed for example in ordinary Dressler kilns. As shown air is withdrawn from the cooling zone A^3 of the kiln by a fan R connected to the tunnel P . The heated air thus withdrawn may be utilized in the various ways in which the hot air from the cooling zone of an ordinary kiln is ordinarily utilized. With the construction shown 45 in Fig. 7 ordinarily but one or two furnaces C at each side of the kiln are required to obtain a flashing or salt glazing effect. The same kiln atmosphere and the same kiln atmosphere circulation can be had with the construction shown in Fig. 7 as with the construction first described.

Having now described my invention, what I claim as new and desire to secure by Letters Patent, is:

1. The method of treating ceramic ware which consists in gradually heating the ware to a high temperature by passing the ware through a continuous tunnel kiln comprising a heating up zone in which the ware re-

ceives the major portion of its heating and in which an oxidizing atmosphere is maintained, and a successive kiln zone in which further heat is supplied to the ware and the latter is subjected to a non-oxidizing atmosphere by contact with hot gases passed into the kiln chamber at its top and withdrawn from the kiln chamber at its bottom.

2. The method of operating a continuous tunnel kiln which consists in passing hot furnace gases into the kiln chamber at the top of a high temperature zone thereof and withdrawing them from the kiln chamber at the bottom of said zone while still retaining the major portion of their available heat and then passing the gases through conduits or muffles in an adjacent elongated heating up zone of the kiln to thereby transmit the remainder of the available heat in the gases to goods passing first through the preheating zone and then through said high temperature zone of the kiln.

3. The combination in a continuous tunnel kiln, of an elongated heating up section, an adjacent shorter high temperature section, and heating means for the kiln comprising provisions for passing burning gases into said high temperature kiln section at its top and withdrawing the heating gases from that section at its bottom, internally heated chambers in the heating up section of the kiln arranged at the sides of the goods pathway therethrough, provisions for passing the heating gases withdrawn from the high temperature section through said chambers, and provisions for directing a convection current circulation of the kiln atmosphere upward past said chambers and downward through the goods pathway.

4. The combination in a continuous tunnel kiln, of an elongated heating up section, an adjacent shorter high temperature section, and heating means for the kiln comprising provisions for passing burning gases into said high temperature kiln section at its top and withdrawing the heating gases from that section at its bottom, chambers in the heating up section of the kiln arranged at the sides of the goods pathway therethrough, provisions for passing the heating gases withdrawn from the high temperature section through said chambers, and provisions for directing a convection current circulation of the kiln atmosphere upward past said chambers and downward through the goods pathway.

5. In a continuous tunnel kiln comprising a heating up section and an adjacent open fire heated section, the combination of furnaces at the sides of the open fire heated section, walls interposed between the furnaces and the goods receiving space of the kiln for causing the furnace gases to pass into the goods receiving space at the top of the latter, conduits formed in said walls and

- communicating with the goods receiving space adjacent the bottom of the latter for withdrawing furnace gases from the kiln chamber, internally heated chambers arranged in the heating up section of the kiln at the opposite sides of the goods receiving space, and baffles fitting snugly about the space traversed by the goods adjacent the junction of the two kiln sections to restrict longitudinal flow of the kiln atmosphere from one section into the other. 25
6. In a continuous tunnel kiln comprising a heating up section and an adjacent open fire heated section, the combination of furnaces at the sides of the open fire heated section and walls interposed between the furnaces and the goods receiving space of the kiln for causing the furnace gases to pass into the goods receiving space at the top of the latter, conduits formed in said walls and communicating with the goods receiving space adjacent the bottom of the latter, and muffles or heating chambers arranged in the heating 30
- 10
- 15
- 20
- up section of the kiln at the opposite sides of the goods receiving space and communicating with said conduits at the junction of said kiln sections, draft provisions for causing heating gases to pass out of the kiln chamber into said conduits and thence through said chambers. 35
7. In a continuous tunnel kiln for first heating and then cooling goods, passing through the kiln, the improvement which consists in a cooling zone section formed with air chambers in its walls and regulable air passages distributed along the length of the kiln and connecting the air chambers to the atmosphere, and also to the interior of the kiln chamber, and means for causing a longitudinal flow through the air chambers toward the hot end of the cooling zone section. 40

Signed at Cleveland, in the county of Cuyahoga and State of Ohio, this 9th day of December, A. D. 1920.

HARRY M. ROBERTSON.
